UNITED STATES PATENT OFFICE.

EDWARD D. SCHMITT, OF BALTIMORE, MARYLAND, ASSIGNOR, BY DIRECT AND MESNE ASSIGNMENTS, TO THE PURE FOOD PROCESS COMPANY, OF BALTIMORE, MARYLAND, A CORPORATION OF MARYLAND.

SEALING-HEAD FOR APPLYING JAR CAPS OR CLOSURES.

981,009.

Specification of Letters Patent. Patented Jan. 10, 1911.

Application filed December 6, 1909. Serial No. 531,740.

To all whom it may concern:

Be it known that I, EDWARD D. SCHMITT, a citizen of the United States, residing at Baltimore city, State of Maryland, have invented certain new and useful Improvements in Sealing-Heads for Applying Jar Caps or Closures, of which the following is a specification.

This invention relates to improvements in sealing heads for applying metal caps to jars.

The invention resides in the construction of the head and it will be understood that the jar to be sealed or capped may be moved toward the head, or the head moved toward the jar, which may be supported upon a suitable support below the head, it making no difference, so long as the desired pressure necessary to apply the cap, is brought about.

The object of the invention is to provide a simple durable and effective mechanism for seating the cap or closure firmly upon the jar and indenting the flange thereof at intervals into locking engagement with the locking shoulder on the jar neck.

In the drawings illustrating the invention: Figure 1 is a central partially sectional view of the sealing head, with the parts in normal position; Fig. 2 is a similar view showing the position the parts assume in applying the seal; Fig. 3 is a rear elevation of two of the seal indenting fingers; Fig. 4 is a top plan view and section of the ring which contains the devices for yieldingly operating the locking fingers.

Referring to the drawings, the numeral 1 designates the upper part of the head casing, which is provided with a bore 2 for the reception of a sealing spring 3 which rests at its lower end upon the circular cross-head 4 of the seal applying plunger 5, which head rests upon an annular shoulder 6 in the lower part of the bore 2. The plunger stem 45 is provided with an annular inclined shoulder 7, the purpose of which will presently be described, and a bearing portion 8 which is hollowed out as indicated at 9 and adapted to fit over the cap or closure in the seal applying operation. The lower part of the head is formed of two members 10 and 11, the upper member 10 being externally threaded as indicated at 12, whereby it is connected to the lower enlarged part 13 of

the upper part 1. The member 10 is 55 threaded at its lower edge as indicated at 14, to receive the threads in the upper part of the member 11, whereby the two members 10 and 11 are connected together. The lower edge of the member 10 is provided 60 with a groove 15 extending entirely around its lower edge, which corresponds with a groove 16 in the upper edge of the member 11.

The numeral 17 designates the seal locking fingers, a plurality of which, suitably spaced apart are employed, and adapted, in the sealing operation, to be yieldingly actuated to lock the flange of the seal in locking engagement with the shoulder on the outside of the jar. Each locking finger is formed with a downwardly extending arm 18 provided with an inwardly-turned seal-indenting point 19, and with an upwardly extending arm 20 provided with a head 21 65 engaging a spiral spring 22, each spring being contained within a slidable cut 23 mounted in a radial recess 24 in a ring 25, said ring being bolted to the upper part of the member 10 by bolts 26. Each seal locking finger is provided with a short integral extension 27, each of which is provided centrally and at opposite ends with short studs 28. These extensions fit snugly in the annular groove formed by the two corresponding 70 80 85 90 95 100 105 grooves 15 and 16 in the members 10 and 11 and are adapted to rock and cause the seal indenting fingers to be forced into engagement with the flange of the cap at intervals to lock it under the locking shoulder of the receptacle to be closed. The cups 23 are beveled at their inner ends as designated at 29, which ends extend into the path of movement of the inclined or beveled shoulder 7 of the shank of the plunger, so that when the plunger is raised, said portion 7 will engage the beveled ends of the cups and force them outward simultaneously, thus causing the locking fingers through the medium of the spiral springs within the cups, to be rocked upon their pivots to bring their lower indenting ends into action to lock the seal.

The upper part of the head casing has integral therewith a web 30, which connects the head with a cylindrical sleeve 31 which receives the rod 32, which may be reciprocated to move the head to and from a suitable bottle support. If the head is to remain

stationary, and the jar support moved upward toward the head, the rod 32 may support the head in proper fixed position relative to the jar support.

- 5 In operation, the head is depressed, or the bottle support is moved upward, toward the head, as the case may be, and in either event, the jar together with the cap is brought against the lower portion 8 of the plunger, 10 forcing said plunger upwardly against the pressure of the sealing spring 3. The upward movement of the plunger brings the inclined bevel shoulder 7 on the shank of the plunger into engagement with the beveled ends 29 of the sliding cups 23 within the radial recesses of the ring 25, causing the devices to simultaneously move outward, compressing the springs 22 slightly, and causing them to act yieldingly against the upper 15 ends 21 of the seal locking fingers, thus forcing the lower indenting ends of the fingers inward, where they engage the flange of the seal at intervals. Upon withdrawal of the jar, the plunger is returned to normal position by the sealing spring and its downward movement is limited by a ledge 33 in the lower part of the casing.

Having thus fully described my invention, what I claim is:

- 30 1. A head for applying caps or closures to jars and like receptacles, comprising a casing, a spring pressed seal applying plunger in said casing, having a portion adapted to bear upon the cap and a shank having an annular inclined beveled shoulder thereon, a ring surrounding said plunger and having a series of recesses therein, a cup-shaped device in each of said recesses, said device having beveled ends extending into the path 35 of movement of the inclined or beveled shoulder on the plunger shank, a plurality of seal locking fingers rockably supported in the lower part of the head casing, and having lower ends adapted to indent the 40 cap or seal at intervals, for the purpose set forth, springs interposed between the cup-shaped device and the upper ends of said fingers, whereby, when the plunger is raised, the fingers will be yieldingly rocked to act 45 upon the flange of the cap.
2. In a sealing head for applying caps or closures to jars and like receptacles, the combination with a spring-pressed plunger having a portion adapted to bear upon the jar cap or closure, said plunger having a shank having a beveled or inclined shoulder thereon, a ring surrounding said plunger and having radial recesses therein, a sliding cup-shaped device in each recess, provided 50 with inclined inner ends, extending into the path of movement of the shoulder upon the shank, a plurality of seal locking fingers having extensions that bear in the lower part of the head casing, of a means for 55 spacing said fingers apart, the fingers being

provided, at their lower ends with seal indenting points, for the purpose set forth, a spiral spring interposed between each sliding cup and the upper end of the seal locking fingers, whereby, when the plunger 70 is moved upward, and the cups moved laterally, the fingers will be rocked to act upon the flange of the cap or closure.

3. A sealing head for applying caps or closures to jars or like receptacles, comprising a casing having a lower part formed of two separable members, an annular groove in each member, at the point of juncture of said members, a plurality of seal locking fingers having extensions rockably resting in the groove between said members, means for suitably spacing from each other, the extensions, and thereby the fingers, a spring pressed sealing plunger within said casing and having a shank provided with an annular inclined or beveled shoulder, a ring surrounding the plunger shank and carrying a plurality of sliding cup-shaped devices having inner beveled ends in the path of movement of the shoulder or inclined portion of the plunger shank, spiral springs interposed between the sliding devices and the upper ends of the locking fingers, whereby when the plunger is raised, the locking fingers, through the medium of the cup-shaped devices and the springs, the seal locking fingers will be actuated.

4. A head for applying caps or closures to jars and like receptacles, comprising a casing, a spring-pressed seal applying plunger in said casing having a portion adapted to bear upon the cap and a shank having a cam surface thereon, a plurality of seal locking fingers rockably supported in the lower part of the head casing and having lower ends adapted to indent the cap or seal at intervals, a plurality of devices surrounding the plunger shank, and having cam surfaces adapted to be engaged by the cam surface on the plunger shank to force said devices outwardly upon the upward movement of the plunger, springs interposed between said devices and the rockable seal locking fingers, whereby the lower ends of said fingers are simultaneously forced yieldingly inward to act upon the flange of the cap.

5. A head for applying caps or closures to jars and like receptacles, comprising a casing, a spring pressed seal applying plunger in said casing having a portion adapted to bear upon the cap and a shank having a cam surface thereon, said casing having a lower part formed of two separable members, each having an annular groove at the point of juncture of said members, a plurality of seal locking fingers having extensions rockably resting in the groove between said members, means for spacing said extensions from each other, and thereby the fingers, a plurality of devices surrounding

the plunger and having cam surfaces adapted to be engaged by the cam surface upon the plunger shank upon the upward movement of the plunger, to force said devices laterally simultaneously, a spring interposed between each device and each seal locking finger whereby, upon the upward movement of the plunger the lower ends of the seal

locking fingers are simultaneously forced inward to act upon the flange of the cap. 10

In testimony whereof I affix my signature in presence of two witnesses.
